9 Claims. (Cl. 89—128)

This invention relates to automatic guns operated by recoil actuated barrels and more particularly to the bolt mechanisms therefor.

It is an object of this invention to provide for such automatic guns a bolt which is easily installed within the receiver as it is unattached to any other member and lies on supporting slideways for free reciprocal flight.

It is another object of this invention to provide for such a bolt a firing pin which is seared by a rotary bolt lock to assure positive locking of the bolt before the firing pin is released.

It is a further object of this invention to provide such a bolt lock which, during the rotation thereof to the unlock position, completes the retraction of the firing pin to the cocked position and then retains it therein until the bolt is locked.

It is still another object of this invention to provide such a rotary bolt lock on which locking wings are eccentrically disposed so that the bolt is allowed to move rearwardly under blow back forces during rotation of the bolt lock to the unlock position and thereby gradually break loose the fired cases from the barrel chamber to reduce the impact between the extractor claw and rim of the fired cases when the bolt, after being unlocked, is accelerated to the recoil position.

It is another and still further object of this invention to provide for such a bolt mechanism an accelerator which blocks the disengagement of the extractor from the extractor grooves of the fired cases during initial extraction thereof from the gun barrel.

It is a further and still another object of this invention to provide in such a bolt mechanism a torsional type bolt return spring for greater efficiency of the bolt mechanism and for facilitating the removal of the bolt from the gun receiver because this type of spring does not require the bolt to be connected to any other member.

The specific nature of the invention as well as other objects and advantages thereof will clearly appear from a description of a preferred embodiment as shown in the accompanying drawings in which:

FIG. 1 is a sectionalized elevational view of a gun with the bolt mechanism of this invention incorporated therein and shows the bolt in recoil position;

FIG. 2 is a view taken along line 2—2 of FIG. 1;

FIG. 3 is a view taken along line 3—3 of FIG. 1;

FIG. 4 is a view taken along line 4—4 of FIG. 1;

FIG. 5 is a view taken along line 5—5 of FIG. 1;

FIG. 6 is an enlarged longitudinally cross-sectioned side view of the gun showing the bolt adjacent recoil position during recoil flight;

FIG. 7 is a fragmentary view similar to FIG. 6 but showing the bolt locked in the battery position and the firing pin released;

FIG. 8 is a view taken along line 8—8 of FIG. 7;

FIG. 9 is a view taken along line 9—9 of FIG. 8;

FIG. 10 is a view similar to FIG. 8 but showing the cocking rotor engaged with the firing pin and the barrel extension in its rearward position; and

FIG. 11 is a perspective view of the bolt lock.

2

Shown in the figures is a machine gun 12 provided with a rectangular receiver 14 which slidably supports a barrel assembly 16 having a barrel extension 18 with a barrel 20 replaceably joined within the front end thereof for extension from the front end of the receiver. The portion of barrel extension 18 which extends rearwardly from the breech of barrel 20 is bifurcated to form a right leg 22 and a left leg 24 with an ejection passageway 26 therebetween to provide a clearance for the ejection of fired cases downwardly from the barrel and out the bottom of receiver 14.

A back plate 28 with a bolt buffer mechanism 30 contained therein is slidably installed in the rear end of receiver 14 by vertically disposed tongue and groove means. The distance between back plate 28 and the front end of receiver 14 is sufficiently greater than the length of barrel extension 18 so that barrel assembly 16 may reciprocate therein, responsive to recoil forces produced by the discharge of a cartridge in barrel 20, to power gun 12 for automatic operation. A blind hole 31 extends forwardly into left leg 24 from the rear end thereof and such hole sliding receives a rod 32 which has contact with back plate 28. A compressible coil spring 34 is disposed in hole 31 between the front end thereof and rod 32 so as to be energized thereby during recoil movement of barrel assembly 16 for returning the barrel assembly to the forward position thereof. A spring-biased catch 35 is arranged in the left side of receiver 14 for releasable engagement with barrel extension 18 when in the forward position to retain the barrel extension therein. A plunger 33 extends slidingly through left leg 24 from ejection passageway 26 for registry with catch 35, as is best shown in FIG. 5, when barrel extension 18 is in the forward position, so that an inner displacement of the plunger will actuate the catch to an unlatched position.

The top surfaces of right leg 22 and left leg 24 are planarly formed and smoothly surfaced to provide slideways 36 for supporting a bolt 38 for reciprocation therewith between a recoil and a battery position.

Bolt 38 is received by ejection passageway 26 and is provided with a right flange 39 and a left flange 40 which extend laterally from respective sides of the bolt to slidably contact slideways 36 and thereby support the bolt for its reciprocation in the ejection passageway. The flanges 39 and 40 are retained in contact with the slideways 36 by a feed tray 41 which is hingedly mounted on the top of receiver 14 and which is provided with a pair of rails 42 disposed along the underside for sliding contact with the top of the flanges. A cover 37 is hingedly mounted on receiver 14 over feed tray 41 so that bolt 38 is easily installed within the receiver after the cover and feed tray 41 are raised because by being unattached to any other member the bolt need only be laid upon slideways 36. A charging device (not shown) actuates bolt to the recoil position to be seared therat as hereinafter described.

Catch 35 and plunger 33 are disposed so as to be actuated by bolt 38 when approaching the battery position to release barrel assembly 16 from receiver 14 for recoil movement therein.

Bolt 38 carries, as will be explained in greater detail hereinafter, a rammer 43, an extractor 44, a cocking rotor 46, a firing pin 48 and a bolt lock 50. Rammer 43 is pivotally mounted on the top of bolt 38 for engagement with the cartridges successively indexed by a feeding mechanism 51 in a feed throat 52 of feed tray 41 for transferring the cartridges therefrom into the chamber of barrel 20 during the travel of the bolt to battery position.

Extractor 44 is pivotally mounted on bolt 38 within an accommodating recess therein so that a claw 54 terminating the front end of the extractor extends forwardly from the front face of the bolt for engagement with the extractor groove of the cartridge chambered in barrel 20 when the bolt goes into battery position. A ledge 56 (FIG. 6) is formed on the bottom of extractor 44 under claw 54 so as to be exposed forwardly of the front face of bolt 38. A spring 58 is disposed between the bottom of extractor 44 and the bottom of the accommodating recess in the bolt for biasing the extractor upwardly to the cartridge engaging position.

Firing pin 48 is slidably mounted in bolt 38 by means of a stepped recess 60 which permits longitudinal reciprocation of the firing pin between a cocked and a firing position. Firing pin 48 includes a cylindrical spring housing 62, a rectangular body 64 which extends integrally forward from the front end thereof and a cylindrical striker 66 which is fixedly secured to the body portion for longitudinal extension therefrom. As best shown in FIG. 6, housing 62 is provided with a cylindrical hole 68 which extends forwardly from the rear end thereof to a terminating wall 70 and such hole slidably receives a sleeve 72 the rear end of which is closed by a base 73. A compressible coil spring 74 is disposed in sleeve 72 with the opposite ends having contact with base 73 and wall 70 so that the spring is compressed therebetween when the sleeve and housing 62 are telescoped together.

The cross-sectional area of body 64 is smaller than that of housing 62 so that a portion of the front end thereof is exposed on opposite sides of the body and such exposed portion is contactable with a shoulder 75 in recess 60 when firing pin 48 is in the firing position. The front end of housing 62 is also contactable by cocking rotor 46, as hereinafter described, for initiating the displacement of firing pin 48 to the cocked position. The front end of body 64 is recessed to form thereon an arcuate surface 76 (FIGS. 6 and 7) which extends rearwardly and downwardly from the front end to the bottom of the body and which is contactable, as hereinafter described, by bolt lock 50 for holding the firing pin 48 in the cocked position.

Firing pin 48 is secured within bolt 38 by a retainer 78 which is installed in the bolt by vertically disposed tongue and groove means in back of sleeve 72 after the sleeve is pressed forwardly into housing 62 for preloading spring 74. A key 80 extending transversely across the bottom of recess 60 engages a keyway 81 in housing 62 for preventing rotational displacement of firing pin 48 while permitting longitudinal displacement thereof between the cocked and firing positions.

Bolt lock 50 is journaled in bolt 38 for rotation between a lock and an unlock position by means of a bore 82 which extends laterally therethrough. Bore 82 is located so that surface 76 on firing pin 48 is disposed in the bore when the firing pin is in the firing position and is also disposed so that the axis thereof is located below the longitudinal axis of the firing pin and at right angles thereto.

Bolt lock 50, which is best shown in FIG. 11, includes a cylindrical mount 84 which is rotatably received by bore 82 and which has a length similar thereto. The ends of mount 84 are perpendicular to the longitudinal axis thereof and integrally extending from each of such ends is a wing 86. The wings 86 function, as hereinafter described, to releasably lock bolt 38, when in the battery position, to barrel extension 18.

Mount 84 is recessed by an arcuate channel 88 to provide a clearance for striker 66 during rotation between the lock and unlock positions. Channel 88 includes a front section 89 the longitudinal axis of which is disposed approximately parallel to the axis of striker 66 when bolt lock 50 is in the lock position and a rear section 91 the longitudinal axis of which is approximately parallel

to that of the striker when the bolt lock is in the unlock position. Thus, front section 89 and rear section 91 are angularly related and converge at approximately the center of bolt lock 50. Rear section 91 is enlarged to provide a pocket 90 for receiving body 64 of firing pin 48 when the firing pin is in the firing position. Pocket 90 includes a floor surface 92, which is arranged so as to align with the bottom of body 64 when bolt lock 50 is nearly rotated to the lock position, and an end wall 94 which is disposed at right angles to the floor and is spaced sufficiently forward in mount 84 to permit unrestricted displacement of firing pin 48 to the firing position. A pair of camming surfaces 95 are formed on both sides of rear section 91 of channel 88 eccentric to mount 84 as best shown in FIG. 11. The intersection of floor surface 92 with the camming surfaces 95 forms an interrupted rear edge 96 which is disposed, as shown in FIG. 7, so as to clear the bottom of body 64 for release of firing pin 48 just before bolt lock 50 reaches lock position during rotation thereto.

Cocking rotor 46 is mounted on bolt 38 between a pair of skirts 98 (FIG. 9) which extend laterally from left flange 40 and which are spaced vertically to permit insertion of the cocking rotor therebetween. A pin 99 extends vertically through rotor 46 and the skirts 98 to provide an axle for the rotation of the rotor. Rotor 46 includes a tang 100, which is contactable with the front end of housing 62, as best shown in FIGS. 8 and 10, for displacing firing pin 48 sufficiently to move body 64 out of pocket 90 when the rotor is rotated. The rotation of rotor 46 is achieved by the successive engagements of a primary cog 102 and secondary cog 103 thereon with a cam surface 104 on the inside of the adjacent side of receiver 14 during initial movement of bolt 38 from battery position. When firing pin 48 is retracted by rotor 46, surface 76 on the front of body 64 is positioned for contact by the camming surfaces 95 on mount 84 when bolt lock 50 is rotated from the lock position. Camming surfaces 95 are so generated that the rotary contact thereof with surface 76 of firing pin 48 continues the retraction of the firing pin to the cocked position as the bolt lock completes its rotation to the unlock position.

The wings 86 are eccentrically disposed on the ends of mount 84 so that the undersides of the wings lie approximately along the diameter of the mount and, when bolt lock 50 is in the unlock position, the undersides are in alignment with the undersides of the respective ones of the flanges 39 and 40, so as to have sliding contact with the slideways 36, and the top sides of the wings are in longitudinal alignment with the top surfaces of the respective ones of the flanges 39 and 40 and are disposed for sliding contact with the rails 42. Each of the wings 86 is provided at the rear end with a locking surface 106 which is angularly disposed relative to the longitudinal axis of the associated wing so as to be substantially vertically disposed as shown in FIG. 9 when bolt lock 50 is in the lock position.

Initial displacement of bolt lock 50 from the unlock to the lock position is achieved by a cam block 108 which is mounted on right leg 22 of barrel extension 18 at the front end of the slideway 36 thereon so that a cam surface 110 on the rear end of the cam block is engaged by the front end of the right one of the wings 86 when bolt 38 is adjacent battery position.

A plunger 112 is mounted on the inside of receiver 14 so as to be partially received in a notch 109 in the left one of the wings 86 immediately before the right one of the wings contacts cam surface 110 for locking bolt lock in the lock position. Plunger 112 is biased rearwardly by a spring 113 whereby, when the right one of the wings 86 contacts cam surface 110 and initiates the rotation of bolt lock 50 to the lock position, such spring is compressed. Provided on the rear end of plunger 112 is a cam surface 115 which extends upwardly and forwardly

therefrom and which is disposed for engagement with the bottom front corner of the left one of the wings 86 after rotation of bolt lock 50 is initiated by cam surface 110. The bias of cam surface 115 and the tension of loaded spring 113 completes the rotation of bolt lock 50 to the lock position. The shape of cam surface 110 is generated to accelerate bolt lock 50 to an angular velocity which is appreciably greater than and proportional to the linear velocity of bolt 38 so that, no matter how high the bolt velocity is, it is impossible for the bolt to bounce out of battery position before the bolt lock reaches the lock position.

When bolt lock 50 is rotated to the lock position, wherein in the wings 86 are angularly disposed relative to the longitudinal axis of bolt 38, the locking surfaces 106 are received by V-shaped recesses 114 formed in the slide-ways 36. The rear sides of the recesses 114 form engaging surfaces 116 which, as shown in FIG. 9, are so angularly disposed that, when the locking surfaces 106 are pressed rearward thereagainst by the rearward pressure applied to bolt 38 through the discharge of a cartridge in barrel 20, bolt lock 50 is energized in the direction of locking and thereby positively locks the bolt in the battery position. Bolt lock 50 is actuated to the unlock position by cam surfaces 118 which terminate respectively at the front ends of the rails 42 and which are disposed so that bolt 38 is unlocked from barrel assembly 16, during recoil travel thereof, when the gas pressure in barrel 20 is reduced to safe limits.

The recoil energy in barrel assembly 16 is transferred to bolt 38 for reciprocation to and from the recoil position by accelerator device 120 which is mounted within receiver 14 under barrel extension 18. Accelerator device 120 includes a rectangular housing 122 which is located at the rear end of receiver 14 and which is slidably mounted therein on longitudinally disposed tongue and groove means 121 (FIG. 1). Housing 122 is backed up by back plate 28. A tubular casing 124 (FIG. 1) extends forwardly from housing 122 along the right side of the receiver and such casing is provided with a longitudinal bore 126 which extends rearwardly from the front end and which is counterbored from the front end, as noted at 128, to form an annular shoulder 130. A buffer device 132 is installed in counterbore 128 and such device includes a cylindrical head 134 having approximately the same diameter as the counterbore so as to be slidably received thereby. An annular flange 135 around the front end of head 134 limits the movement thereof into counterbore 128. A rod 136 extends axially from head 134 into counterbore 128 and slidably mounted thereon is a washer 138 which is backed by a nut 140 threaded to the end of the rod. A compressible coil spring 142 is disposed on rod 136 between head 134 and washer 138 and is preloaded by tightening nut 140 against the washer. When buffer device 132 is installed in counterbore 128, washer 138 contacts shoulder 130 therein and the length of rod 136 is arranged so that flange 135 is spaced from the end of casing 124 to permit resilient rearward displacement of head 134 and the rod. A lug 137 (FIGS. 1 and 4) extends inwardly from the right side of receiver 14 for contact with the front end of head 134. Whereby, resilient relative movement is provided between head 134 and accelerator device 120 so that with the accelerator device being backed by back plate 28 the head 134 may be resiliently telescoped into casing 124 when rearward pressure is applied against the head. Moreover, with head 134 having forward contact with lug 137, accelerator device 120 may be forwardly displaced against the bias of spring 142 to telescope casing 124 over the head 134.

A shaft 143 (FIG. 1) extends axially forward from head 134 for engagement by an accelerator lever 144 which is pivotally mounted on barrel extension 18 in the front end of ejection passageway 26. Accelerator lever 144 is pivotally mounted on barrel extension 18 by means

of a pin 145 which extends transversely through the lever approximately midway of the top and bottom thereof. An arm 146 extends laterally from the bottom of accelerator lever 144 for contact with the front end of shaft 143 during recoil movement of barrel extension 18. The top portion of accelerator lever 144 includes a pair of laterally spaced fingers 148 which contact the front face of bolt 38 on opposite sides of extractor 44. When bolt 38 is locked to barrel extension 18 during initial recoil movement thereof, accelerator lever 144 is prevented from pivotal movement whereby the rearward movement of the barrel extension is transferred to buffer device 132 to press head 134 resiliently into counterbore 128. Consequently, when bolt 38 is unlocked from barrel extension 18 and accelerator lever 144 is free to pivot, the resiliency of the loaded spring 142 acting against the accelerator lever propels the bolt rearwardly at an accelerated velocity. Provided on the inside of each of the fingers 148 is a lug 149 (FIGS. 4 and 5) which is contactable by ledge 56 of extractor 44 to prevent disengagement of claw 54 from the extractor groove of a fired case during initial extraction from barrel 20.

When bolt 38 goes into recoil position, sufficient energy is transferred therefrom to a bolt return spring mechanism 150 to return the bolt to battery position with the remaining energy being absorbed by buffer mechanism 30. Bolt 38 is secured in the recoil position by a latch 152 which is pivotally mounted on the top of housing 122 of accelerator device 120 and is disposed for releasable engagement with a stop 153 which extends integrally downward from the bottom of the bolt. As accelerator device 120 is disposed for resilient forward movement in receiver 14, the shock of impact between latch 152 and bolt 38 is cushioned by accelerator buffer device 132.

Bolt return spring mechanism 150 includes a cage 154 which is slidably installed in receiver 14 above barrel extension 18 on longitudinally disposed tongue and groove means and is secured in position by back plate 28. Cage 154 includes a pair of laterally spaced flanges 156 which extend rearwardly from an inverted U-shaped, cross-support 157 and which support therebetween a laterally disposed rod 158. Rod 158 is inserted through the coils of a pair of double-armed springs 160 having outside arms 162, which are curved to contact the top of cross-support 157, and inside arms 164, which have contact with the rear side of a cross-piece 166 extending across the underside of cross-support 157 so that such inner arms may be actuated rearwardly to wind the springs. The ends of the inside arms 164 extend forwardly and then outwardly so as to be contactable by the rear end of bolt 38 when adjacent recoil position for winding the springs 160 and transfer thereto sufficient energy for returning the bolt to battery position. Latch 152 is disposed so as to engage stop 153 to hold bolt 38 in the recoil position, when the springs 160 are wound, whereby, the bolt is propelled by the springs to the battery position when released by latch 152.

Operation

Gun 12 is fired from the open bolt position, with bolt 38 seared in recoil position by latch 152, so that a cartridge is never retained in a hot chamber to create a "cook-off" hazard between bursts. A burst is initiated by actuating latch 152 to release bolt 38 which, when released, is propelled in free flight to battery position through the energy transferred to bolt return springs 160 when the bolt was actuated to the recoil position. During the forward flight of bolt 38, a cartridge indexed in feed throat 52 is picked up by rammer 43 and pushed forwardly thereby into barrel 20. Bolt lock 50 is retained in the unlock position during such flight through the sliding contact of the wings 86 between rails 42 and slide-ways 36.

When bolt 38 is adjacent battery position, plunger 33 is contacted thereby to actuate catch 35 for release of

barrel assembly 16 from receiver 14 so that it is free for recoil displacement when the chambered cartridge is discharged. At approximately the same time, plunger 112 is contacted by the left one of the wings 86 and is pressed forwardly to load spring 113 and apply the energy in the spring under the front end of such wing. The right one of the wings 86 then contacts cam surface 110 of cam block 108 to initiate the rotation of bolt lock 50 from the unlock to the lock position. Plunger 112 continues the rotation of bolt lock 50 until locking surfaces 106 thereon are in full contact with engaging surfaces 116. Because of the rearward bias of plunger 112 and the engagement thereof with notch 109 in the left wing 86, bolt lock 50 is secured against displacement from the lock position.

At a point where bolt lock 50 has rotated to a safely locked position, but before it has reached full rotation, rear edge 96 on the bolt lock clears the bottom of body 64 of firing pin 48 which is freed thereby to be driven forwardly by spring 74 to strike the primer of the chambered cartridge for discharge thereof. Bolt lock 50 continues to locked position as firing pin 48 goes forward to discharge the chambered cartridge.

Upon the discharge of the chambered cartridge, barrel assembly 16, previously unlocked from receiver 14, is energized for rearward movement in the receiver against the resistance of spring 34 to carry with it bolt 38 which is locked by bolt lock 50 to barrel extension 18. As bolt 38 is prevented from movement relative to barrel assembly 16, accelerator lever 144 is held against pivotal displacement and, therefore, the rearward movement of the accelerator lever with the barrel assembly is transferred to buffer device 132 to load spring 142 therein. While accelerator lever 144 is in contact with the locked bolt 38, it is held in the upright position so that the lugs 149 thereon are disposed under ledge 56 of extractor 44 to block the disengagement of claw 54 from the extractor groove of the fired cartridge case to assure positive extraction thereof.

During the initial recoil movement of barrel assembly 16, cog 102 of cocking rotor 46 contacts cam surface 104 to rotate the cocking rotor. Whereby, tang 100 is actuated against the front end of housing 62 to retract firing pin 48 sufficiently for striker 66 to be extracted from the primer of the fired cartridge case and for body 64 to be clear of pocket 90 in bolt lock 50. Also, during initial recoil movement of barrel assembly 16, locking plunger 112 contacts an abutment 170 (FIG. 8) fixed to receiver 14 which causes the cocking plunger to become disengaged from notch 109 in the lower surface of the left one of wings 86 of bolt lock 50. Thus, bolt lock 50 is free for rotation when the top front ends of the wings 86 contact the cam surfaces 118 on rails 42. When the wings 86 contact cam surfaces 118, bolt lock 50 is rotated to the unlock position, with camming surfaces 95 on mount 84 rotatably engaging surface 76 at the front end of firing pin body 64 to complete the retraction of firing pin 48 to the cocked position during the rotation of the bolt lock to the unlock position. Because of the eccentric mounting of the wings 86 on mount 84, when bolt lock 50 is rotated to the unlock position, the locking surfaces 106 on the wings are cammingly actuated along the engaging surfaces 116 of the recesses 114 to gradually allow displacement of bolt 38 rearwardly through blow back forces. Thus, the fired cartridge case is gradually broken loose from barrel 20 to reduce the impact between claw 54 and the case when bolt 38 is accelerated for recoil flight.

When bolt 38 is fully unlocked from barrel assembly 16, the loaded accelerator buffer device 132 acts to pivot accelerator lever 144 against the front end of the bolt to catapult the bolt rearwardly in free flight to the recoil position carrying with it the fired case which, when contacted by an ejector 168 depending from feed tray 41, is ejected through ejection passageway 26 and out the

bottom of receiver 14. In the meantime, the recoil energy in barrel assembly 16 is absorbed by spring 34 which uses the transferred energy to return the barrel assembly to the forward position wherein it is secured by catch 35.

When bolt 38 is adjacent recoil position in its rearward flight, it engages the inside arms 164 of the springs 160 in bolt return spring mechanism 150 to wind the springs and then contacts buffer mechanism 30 which absorbs the remaining recoil energy in the bolt. If latch 152 has not been released to hold bolt 38 in the recoil position, the bolt is thrown forwardly in counterrecoil by the springs 160 and buffer mechanism 30 to initiate another firing cycle.

From the foregoing it is clearly apparent that there is provided herein a bolt which, among its many advantages, is easily removed from the receiver by raising the cover and feed tray as it is unattached to any other member. Furthermore, firing before the bolt is locked is prevented by the firing pin being seared by the bolt lock which cooperates with a cocking rotor in retracting the firing pin to the cocked position. Extraction of the firing case, too, is facilitated through the rearward displacement of the bolt by the bolt lock during unlocking and having the extractor blocked in engagement with the extractor groove of the fired case by the accelerator. Moreover, the bolt return spring is of torsional type which has a greater efficiency than the conventional helical types. The bolt mechanism is also distinguished for its rugged construction, ease of manufacture and positive operation.

Although a particular embodiment of the invention has been described in detail herein, it is evident that many variations may be devised within the spirit and scope thereof and the following claims are intended to include such variations.

We claim:

1. A bolt mechanism for a firearm having a receiver and a barrel assembly including a barrel and a barrel extension disposed in the receiver for reciprocation responsive to forces produced by the discharge of a cartridge in the barrel, the bolt mechanism including a bolt disposed for free reciprocal flight on the barrel extension, a rotary bolt lock including a cylindrical mount journaled in a bore extending laterally through said bolt, a wing eccentrically disposed on each end of said mount and a locking surface disposed on the rear end of each of said wings so as to be respectively received by a recess in the barrel extension, an engaging surface formed in each one of said recesses for contact by the related one of said locking surfaces when said bolt lock is in the lock position to block rear displacement of said bolt from battery position, said wings being so eccentrically disposed on said mount and said locking surface being so related to said engaging surfaces that gradual rearward displacement of said bolt relative to said barrel is permitted during rotation of said barrel lock from the locked position to an unlocked position, a firing pin slidably disposed in said bolt and biased therein from a cocked to a firing position, said firing pin including a rectangular body, a striker extending forwardly therefrom, an arcuate surface formed in the front end of said body, a recess arranged in said mount for receiving said striker so as to permit rotation of said bolt lock between the lock and unlock position, a pair of camming surfaces formed on opposite sides of said recess so as to cooperate with said arcuate surface on said firing pin body when engaged therewith for completing the retraction of said firing pin to the cocked position when said bolt lock is rotated to the unlock position, a pocket formed at the rear end of said recess for receiving said body to permit the displacement of said firing pin from the cocked to the firing position, and a sear edge formed at the junction of said pocket and said camming surfaces, said sear edge being disposed to release said firing pin for discharge of the cartridge in the barrel when said wings are positioned sufficiently

within said recesses to block rearward displacement of said bolt during rotation of said bolt lock to the lock position.

2. The bolt mechanism as defined in claim 1 and including a cocking rotor mounted on said bolt by means of a vertically disposed axle pin, a cog extending from said rotor for engagement by a cam surface on the receiver during initial rearward displacement of said bolt with the barrel assembly for rotating said rotor, and a tang extending from said rotor for engagement with said firing pin during rotation of said rotor for displacing said firing pin sufficiently to retract said body from said pocket and position said arcuate surface on said body for engagement by the camming surface of said mount when said bolt lock is rotated from the lock position.

3. A bolt mechanism for a firearm having a receiver with a cover and a feed tray hingedly mounted on the top of the receiver to uncover the top thereof when the cover and feed tray are swung open and a barrel assembly with a barrel extension and barrel disposed for longitudinal reciprocation in the receiver between a rear and a forward position responsive to energy transferred to the barrel assembly from the explosion of a cartridge in the barrel, the barrel extension being provided with a left leg and a right leg and a passageway formed therebetween, the bolt mechanism including a bolt slidably received in the passageway, a pair of flanges extending from opposite sides of said bolt for sliding contact with the tops of the right and left legs to slidably support said bolt for reciprocation between a battery and a recoil position and permit assembly of said bolt to the barrel extension from the top of the receiver when the cover and feed tray are open, a pair of rails depending from the feed tray for sliding contact with the tops of said flanges when the feed tray is closed to the receiver to prevent angular displacement of said bolt in its reciprocation, locking means rotatably disposed in said bolt for latching said bolt when in its battery position to the barrel extension for rearward movement therewith, means for unlatching said bolt from the barrel extension when the barrel assembly is adjacent the rear position thereof, an accelerator device energized by the barrel assembly during displacement thereof to the rear position, means for transferring the energy stored in said accelerator device to said bolt after being unlocked from the barrel extension for catapulting said bolt in free flight to the recoil position, and a bolt return spring device mounted on the rear end of the receiver so as to be contacted by said bolt when adjacent the recoil position for propelling said bolt in free flight to the battery position and energized.

4. The bolt mechanism as defined in claim 3 wherein said bolt return spring device includes a torsional spring which is disposed for engagement by said bolt when adjacent recoil position so as to be energized thereby for propelling said bolt to the battery position.

5. The bolt mechanism as defined in claim 3 wherein said bolt return spring device includes a cage, a laterally disposed rod supported by said cage, a pair of torsional springs coiled around said rod, each of said torsional springs having an inner arm contactable by said bolt when adjacent the recoil position for moving said inner arm in a winding direction and an outer arm anchored to said cage so that the winding displacement of said inner arm energizes the related one of said springs.

6. The bolt mechanism as defined in claim 3 wherein said accelerator device includes a casing longitudinally mounted in the receiver at one side thereof, said casing being provided with a longitudinal bore counterbored at the front end to form an annular shoulder in said casing, a buffer device received by said counterbore, said buffer device including a spring buttressed by said shoulder, a head slidingly received by the front end of said counter-

bore for contact with the front end of said spring so as to compress said spring when moved rearwardly thereagainst and a rod extending forwardly from said head, and an accelerator lever mounted in the barrel extension in the ejection passageway by means of a transversal pin extending through said accelerator lever intermediate the top and bottom thereof, said accelerator lever being contactable above said pin with the front face of said bolt, and an arm extending laterally from said accelerator lever below said pin for contact with the front end of said buffer rod, whereby when said bolt is latched to the barrel extension and the barrel assembly is actuated rearwardly the rearward movement thereof is transferred to said rod for compressing said spring so that said accelerator lever is energized thereby for catapulting said bolt to the recoil position when unlatched from the barrel extension.

7. The bolt mechanism as defined in claim 3 wherein
said accelerator device includes a housing slidingly dis-
posed in the receiver on longitudinally disposed tongue
and groove means, a latch pivotally mounted on the top
of said housing for releasable engagement with said bolt
to sear said bolt in the recoil position, a casing extending
integrally forward from said housing along the right side
25 of the receiver, said casing being provided with a longi-
tudinal bore counterbored from the front end to form an
annular shoulder in said casing, a buffer device disposed
within said counterbore, said buffer device including a
spring buttressed by said shoulder and a head slidingly re-
ceived by the front end of said counterbore for limited
rearward displacement into said counterbore to compress
said spring, a lug extending inwardly from the receiver for
contact with the front end of said head whereby said
30 spring is compressed during forward displacement of said
accelerator for cushioning the impact of engagement be-
tween said latch and said bolt, and an accelerator lever
pivotally mounted in said barrel extension and operationally
interposed between said buffer device and said bolt for
35 loading said spring during rearward displacement of said
accelerator for cushioning the impact of engagement be-
tween said latch and said bolt, and an accelerator lever
pivotally mounted in said barrel extension and operationally
interposed between said buffer device and said bolt for
loading said spring during rearward displacement of said
40 barrel assembly to propel said bolt to the recoil position
after being unlatched therefrom.

8. The bolt mechanism as defined in claim 3 wherein said bolt is provided with a spring-biased extractor having a claw which is disposed forwardly of the front face of said bolt for engagement with an extractor groove of the cartridge chambered in the barrel and a ledge disposed under said claw and forwardly of the front face of said bolt, and wherein said accelerator device is provided with means for blocking disengagement of said claw from the extractor groove while said bolt is latched to the barrel extension.

9. The bolt mechanism as defined in claim 8 wherein said accelerator device includes an accelerator lever mounted on the barrel extension within the ejection passage way on a transversal pin extending through said accelerator lever intermediate the top and bottom thereof, said accelerator lever having a pair of fingers which are disposed above said pin for contact with the front face of said bolt on opposite sides of said extractor, and lugs extending from said fingers under said extractor for contact with said ledge when said bolt is latched to the barrel extension for blocking the displacement of said claw from engagement with the extractor groove of the cartridge.
